(57) CLAIM

The ornamental design for a CPAP pressure meter, as shown and described.

DESCRIPTION

FIG. 1 is perspective view of a CPAP pressure meter according to an embodiment of the present invention; FIG. 2 is a first elevational view of a CPAP pressure meter of FIG. 1;

FIG. 3 is a top view of a CPAP pressure meter of FIG. 1; FIG. 4 is a second elevational view of a CPAP pressure meter of FIG. 1;

FIG. 5 is a third elevational view of a CPAP pressure meter of FIG. 1;

FIG. 6 is a fourth elevational view of a CPAP pressure meter of FIG. 1; and,

FIG. 7 is a bottom view of a CPAP pressure meter of FIG. 1.
